(57) **CLAIM**

The ornamental design for an auxiliary bicycle front fender noise generator, as shown and described.

DESCRIPTION

FIG. 1 is a top plan view of an auxiliary bicycle front fender noise generator showing my new design;

FIG. 2 is a bottom plan view thereof;

FIG. 3 is a rear elevational view thereof;

FIG. 4 is a front elevational view thereof;

FIG. 5 is a left side elevational view thereof;

FIG. 6 is a right side elevational view thereof; and,

FIG. 7 is a front perspective view thereof in inverted position and on a reduced scale with respect to FIG. 1 and shown attached to the front of a bicycle, which is shown in broken lines and forms no part of the claimed design.
